US0D1071724S

(12) **United States Design Patent** (10) Patent No.: **US D1,071,724 S**
(45) Date of Patent: ** Apr. 22, 2025

(54) **CONTAINER CAP**

(71) Applicant: **Chubby Gorilla, Inc.**, Fullerton, CA (US)

(72) Inventors: **Yining Wang**, Hangzhou (CN); **Fengdun Zhang**, Hangzhou (CN); **Xingxin Huang**, Hangzhou (CN); **Ibrahim H. Aboabdo**, Yorba Linda, CA (US)

(73) Assignee: **Chubby Gorilla, Inc.**, Fullerton, CA (US)

(**) Term: **15 Years**

(21) Appl. No.: **29/864,206**

(22) Filed: **May 13, 2022**

(51) LOC (15) Cl. **09-07**

(52) U.S. Cl.

USPC **D9/452**

(58) **Field of Classification Search**

USPC D9/434-435, 440, 445, 447, 449-450, D9/452, 454, 500, 503, 504, 516, D9/520-521, 529, 547, 549, 553, 558, D9/566, 574; D7/602; D24/224

CPC B65D 1/0223; B65D 50/04; B65D 23/00; B65D 2501/00

(57) **CLAIM**

The ornamental design for a container cap as shown and described.

DESCRIPTION

FIG. 1 is a top perspective view of a container embodying the new design.

FIG. 2 is a first bottom perspective view thereof.

FIG. 3 is a second bottom perspective view thereof.

FIG. 4 is a front view thereof.

FIG. 5 is a rear view thereof.

FIG. 6 is a first side view thereof.

FIG. 7 is a second side view thereof.

FIG. 8 is a top view thereof; and,

FIG. 9 is a bottom view thereof.

1 Claim, 5 Drawing Sheets
